UNITED STATES PATENT OFFICE.

JOHN H. GARDELS, OF HILDRETH, NEBRASKA.

SNOW FENCE.

Application filed April 23, 1925. Serial No. 25,443.

The object of my invention is to provide a fence which will effectively prevent the drifting of snow on roads, farm-yards, rail-roads, etc., and to provide a fence for this purpose which has the novel feature of being readily portable and easily erected, and which also is fireproof. I attain these and other objects of my invention by the construction illustrated in the accompanying drawings, in which—

Fig. 1 is a front elevation of one form of my fence, and

Fig. 2 is a horizontal section through same on line 2—2 of Fig. 1.

Like numerals designate like parts in each of the several views.

Referring to Figs. 1 and 2 of the drawings, I provide a fence consisting of longitudinally extending wires 2 with which are interwoven the vertical or transverse wires 1, with a plain open mesh weave. I provide flat metal strips 3, preferably of tin, of sufficient width to substantially fill the space between the adjacent parallel wires 2. The metal strips 3 are threaded in and out alternately between pairs of vertical or transverse wires 1, as shown in Fig. 1. Preferably, but two metal strips are provided between each four horizontal wires leaving a space of one vertical mesh between the metal strips.

It will be noted that I provide spaces or open portions between adjacent longitudinal wires of the fence and that the metal strips intervene only between alternate pairs of the longitudinal wires, thus permitting the wind to sweep through the open portions of the fence and cause the snow to drift and lodge against the fence.

It is also within the contemplation of my invention to provide a metal strip between each two longitudinal wires, thus forming a fence which can also be used for inclosing poultry.

It is my intention that this fence shall be

assembled on steel or concrete posts, thus providing a fence which is absolutely fire-proof, so that weeds and trash that may gather against the fence may be burned and the fence remain unharmed. The fence 50 may be very easily erected or removed when required. It provides a snow break or fence which is but slightly more expensive than ordinary wire fence. It is also well adapted for use around stock yards and also for 55 use as a poultry fence. The fence is also well adapted for use for the cribbing of ear corn, as it sheds snow, dirt, and moisture, but allows air to circulate through the crib. It also protects the corn from being eaten 60 by stock and is fireproof if away from buildings.

What I claim is:

1. A snow fence consisting of a wire fabric having longitudinally and transversely 65 extending wires interwoven in a plain weave of open mesh, flat metal strips interwoven with the wires at spaced intervals to provide intervening open spaces between adjacent longitudinal wires, said metal strips intervening only between alternate pairs of the 70 longitudinal wires to permit wind to sweep through portions of the fence and cause snow to drift against it.

2. A snow fence consisting of a wire fabric having longitudinally and transversely 75 extending wires interwoven in a plain weave of open mesh, flat metal strips extending parallel with the longitudinal wires and interwoven with the wire fabric, said metal 80 strips being alternated with an uncovered strip of the wire fabric to provide open portions between adjacent longitudinal wires, the metal strips intervening only between alternate pairs of the longitudinal wires 85 which permit the wind to sweep between the open portions of the fence and cause the snow to drift and lodge against the fence.

JOHN H. GARDELS.
